UNITED STATES PATENT OFFICE.

WILLIS L. HOLLOWAY, OF WESTBRANCH, IOWA.

VENDING-MACHINE.

SPECIFICATION forming part of Letters Patent No. 738,613, dated September 8, 1903.

Application filed June 2, 1902. Serial No. 109,977. (No model.)

To all whom it may concern:

Be it known that I, WILLIS L. HOLLOWAY, a citizen of the United States, residing at Westbranch, in the county of Cedar and State of Iowa, have invented new and useful Improvements in Vending-Machines, of which the following is a specification.

This invention relates to new and useful improvements in coin-controlled apparatus; and its object is to provide a device of simple construction especially adapted for use in dispensing pencils.

A further object is to provide delivery-controlling means of novel construction operated by a lever which is adapted to be thrown into working relation with said controlling means when the proper coin is placed within the apparatus.

Another object is to employ means for discharging the coin after the delivery of the pencil or other article from the device.

A further object is to provide novel feed mechanism whereby a supply of pencils is held at all times in proper position for delivery, said mechanism being operated by the lever before referred to.

Another object is to provide novel means for placing the operating-lever into engagement with the delivery-controlling mechanism.

With the above and other objects in view the invention consists in the novel construction and arrangement of the several parts, which will be more fully hereinafter described and claimed.

In the drawings, Figure 1 is a front elevation of the apparatus, the upper portion thereof being broken away to show the feed mechanism. Fig. 2 is a side elevation. Fig. 3 is a vertical transverse section through the lower portion of the device. Fig. 4 is a vertical longitudinal section therethrough. Fig. 5 is a detail view of the mechanism for securing together the operating-lever and the delivery-controlling mechanism. Figs. 6 and 7 are detail views of the alternately-movable parts of the delivery-controlling mechanism. Fig. 8 is a fragmentary detail view of a portion of the operating-lever, the secondary lever and its standard, and a coin-pan carried thereby, the parts being shown in position to dump the coin-pan.

Referring to the figures by numerals of reference, 1 is a preferably rectangular casing having a lid 2, adapted to be secured in closed position in any desired manner and extending over two similar hoppers 3, arranged at opposite sides of the vertical partition 4, extending from front to rear of the casing. The compartments formed by this partition are similar, and each contains similar mechanism. I will, therefore, for the sake of convenience describe the mechanism contained in one of the compartments.

The hopper 3 is provided with a series of partitions 5, which converge toward the outlet of the hopper and are adapted to prevent wedging of the pencils after the same have been placed within the hopper. These partitions converge toward each other at their lower portions, thus forming a plurality of chutes, the bottoms of which are just wide enough to permit of the free passage of a single pencil. A shaft 6 is arranged beneath the hopper, and carrier-wheels 7, having a series of recesses 8 in the edges thereof, are mounted upon this shaft and extend upward into the lower end of the hopper 3. The recesses 8, just referred to, are spaced apart such a distance that they will register with the openings in the bottoms of the chutes during the rotation of the carrier-wheels, and in order that the pencils may be readily fed to the carrier-wheels in such a manner that unnecessary clogging may be avoided and the pencils will be continuously removed from the hopper a ratchet-wheel 9 is secured to the shaft 6 and adapted to be engaged by a pawl 10, pivoted to an arm 11, which is loosely mounted on shaft 6 and connected by means of a rod 12 to an arm 13, secured to the fulcrum-pin 14 of an operating-lever 15. This lever extends through a slot 16, formed within the front of the casing 1, and is provided at its outer end with a button 17, whereby the lever may be readily depressed by means of a finger of the operator. The arm 13 is adapted to swing upward when the button 17 is depressed, and thereby partly revolve the wheels 7 upon shaft 6. The lever 15 is mounted upon a standard 18, secured upon the bottom of the casing, and a second lever 19 is fulcrumed at the upper end of this standard and is provided with a threaded end 20, upon

which is mounted an adjustable weight 21. The opposite end of this lever is provided with a cup 22, which is pivoted thereto and provided with a rearwardly-extending inclined 5 arm 23. This lever 19 is adapted to be normally balanced upon its fulcrum, and its cup 22 is normally located at a point directly under the outlet of a coin-tube 24, extending downwardly from a slot 25, arranged in the 10 front face of the casing. An L-shaped arm 26 extends upward from lever 15 at a point within the path of arm 23 and is for the purpose hereinafter more fully described. A connecting-rod 27 is provided near one end 15 with an upwardly-extending ear 28, which is pivoted to the rear end of lever 15. The forward end of this connecting-rod extends upward to and rests upon a pin 29, extending laterally from lever 19, and when said lever 20 19 and its cup 22 move downwardly the lower end of the strip 27 is adapted to swing back into a recess 30, formed within a lever 31, arranged at right angles to lever 15 and adjacent to the rear end thereof. This lever 31 25 is fulcrumed upon a standard 32 and is provided in its upper and lower edges with slots 33. The upper slot receives a pin 34, which is adapted to engage an aperture 35, formed within a slide 36. The remaining 30 slot 33 receives a similar pin, which engages an aperture 37, formed within a slide 38. These slides are mounted in suitable guides formed within the standard 32 at opposite sides of the fulcrum of lever 31, and a series 35 of L-shaped tines 39 extend from a cross-strip 40, secured to the upper slide 36, while a strip 41 is secured to the lower slide 38. This strip 40 normally rests beneath a passage 42, formed between the side wall of the casing and a partition 43, arranged parallel thereto. This partition extends from a point under the carrier-wheels 7 down to a point above a concave outlet-passage 44, which terminates in a receiving-tray 45, arranged upon the outer face of 45 the side of the casing. The ends of the tines 39 normally lie within apertures 46, formed within the partition 43 at a distance above the strip 41 equal to the diameter of the pencil to be discharged.

50 In operation a suitable coin is placed in the slot 25, and tube 24 will guide it downward into cup 22. The additional weight of the coin in said cup will overbalance the adjustable weight 21, and the cup 22 will be carried downward. During this downward movement arm 23 will be swung forward slightly in order to escape the end of arm 26 on lever 15, but will immediately resume its normal position upon passing below the said arm.

55 As lever 19 moves downward the connecting-rod 27 will swing upon its fulcrum 28, and the lower end of said rod will swing into aperture 30, thereby locking levers 15 and 31 together. Lever 15 is then depressed by forcing down button 17. This will cause the arm 26 to press downward upon arm 23 and revolve the cup 22, thereby discharging the

coin which has been deposited therein. The rear end of the lever 15 will move upward and cause lever 31 to swing upon its fulcrum. 70 This movement of lever 31 will retract the lower slide 38 and simultaneously move slide 36 forward. The tines 39 will move into position above the lowest pencil contained within passage 42, while strip 41 will be removed 75 from under the same, and said pencil will drop into the outlet-passage 44 and be received into tray 45, from which it can be removed by the operator. As soon as lever 15 is released it will be returned to normal position by means of a coiled spring 47 or in any other suitable manner, and tines 39 will then be retracted and strip 41 projected, and the pencils contained within the passage 42 will move downward until supported by said 85 strip. The foregoing operation can then be repeated.

Each time the lever 15 is depressed the arm 13, connected therewith, is swung upward. Strip 12 swings pawl 10 against the ratchet 90 wheel 9 and partly revolves the wheels 7, thereby delivering a pencil into the passage 42. In this manner the same number of pencils are contained within the passage 42 at all times.

95 As before described, the apparatus within each compartment within the casing is the same. One compartment, however, may contain pencils adapted to be delivered upon the insertion of a coin of one value, while the remaining compartment may dispense pencils of a different value. The levers and the slots of the two compartments are preferably arranged at opposite sides of the casing.

Lights of glass may be arranged within the 105 sides of the casing, so as to reveal the contents of the passages 42. As the weights 21 are adjustable, the apparatus can be adapted for use with coins of various weights.

In the foregoing description I have shown 110 the preferred form of my invention; but I do not desire to be limited thereto, as I am aware that modifications may be made therein without departing from the spirit or sacrificing any of the advantages thereof, and I 115 therefore reserve the right to make all such changes as fairly fall within the scope of the invention.

Having thus fully described the invention, what is claimed as new is—

120 1. The combination with a casing having an outlet and a hopper above said outlet, of a carrier-wheel interposed between the hopper and outlet and having recesses in its edge, a ratchet revoluble with the wheel, a pawl 125 for revolving the ratchet, an operating-lever, and a rod connecting said lever and pawl whereby the wheel is partly rotated during the depression of the lever.

130 2. In a vending-machine, a hopper to contain the articles to be sold, a plurality of chutes opening from the hopper, a carrier to receive the articles, a passage into which the articles are discharged from the carrier, al-

ternately-operable stops in the passage, and means for operating the stops.

3. In a vending-machine, a hopper to contain the articles to be sold, a plurality of chutes arranged to guide a single article, a carrier to receive the articles from each of said chutes simultaneously, a passage into which the articles are discharged from the carrier, alternately-operable stops in the passage, means for operating the carrier, and means to actuate the stops.

4. In a vending-machine, a hopper to contain the articles to be sold, a carrier to receive the articles, a passage into which the articles are discharged from the carrier, alternately-operable stops in the passage, a standard, a lever fulcrumed on the standard, means to operatively connect the lever and the stops, an operating member and means whereby motion is simultaneously conveyed from the said member to the carrier and the stops.

5. In a vending-machine, a hopper to hold the articles to be sold, a carrier to receive the articles from the hopper, a passage into which the articles are discharged from the carrier, a standard, stops slidably arranged on the

standard, a lever fulcrumed on the standard and engaging the stops to alternately project them into the passage, an operating member, to swing the lever to actuate the stops, and means connecting said operating member and the carrier, whereby the release of an article from the passage operates the carrier to discharge an article into the passage.

6. In a vending-machine, a hopper, to hold the articles to be sold, a carrier to receive the articles, a passage into which the articles are discharged from the carrier, a standard, guides on the standard, stops slidably arranged in the guides, and having pins thereon, a lever fulcrumed on the standard, and having slots to receive the said pins, means to actuate the carrier, and an operating member having connection with the said means and the lever, whereby the carrier and the stops are actuated simultaneously.

In testimony whereof I affix my signature in presence of two witnesses.

WILLIS L. HOLLOWAY.
